(57) **CLAIM**

The ornamental design for an air supply attachment for a helmet as shown and described.

DESCRIPTION

FIG. 1 is a perspective view of a first embodiment of an air supply attachment for a helmet, including an air conduit and an adapter shown in use coupled to a helmet, showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a perspective view of a second embodiment of an air supply attachment for a helmet, including an air conduit and an adapter shown in use coupled to a helmet;

FIG. 9 is a front view thereof;

FIG. 10 is a rear view thereof;

FIG. 11 is a right side view thereof;

FIG. 12 is a left side view thereof;

FIG. 13 is a top view thereof;

FIG. 14 is a bottom view thereof;

FIG. 15 is a perspective view of a third embodiment of an air supply attachment for a helmet, including an air conduit and an adapter;

(Continued)

FIG. 16 is a front view thereof;
 FIG. 17 is a rear view thereof;
 FIG. 18 is a right side view thereof;
 FIG. 19 is a left side view thereof;
 FIG. 20 is a top view thereof;
 FIG. 21 is a bottom view thereof;
 FIG. 22 is a perspective view of a fourth embodiment of an air supply attachment for a helmet, including an air conduit and an adapter;
 FIG. 23 is a front view thereof;
 FIG. 24 is a rear view thereof;
 FIG. 25 is a right side view thereof;
 FIG. 26 is a left side view thereof;
 FIG. 27 is a top view thereof; and,
 FIG. 28 is a bottom view thereof.
 The broken lines depict portions of the air supply attachment for a helmet that form no part of the claimed design.
